ROLL HOLDER FOR DISPENSING SANDPAPER

Herman Gordon, 1315 Wright Drive,
Huntingdon Valley, Pa. 19006

Filed Nov. 16, 1970, Ser. No. 26,004

Term of patent 14 years

Int. Cl. D19—99

U.S. Cl. D59—2 A

FIG. 1 is a top perspective view of a roll holder for dispensing sandpaper showing my new design;

FIG. 2 is a side elevational view thereof, the side opposite being a mirror image thereof;

FIG. 3 is a top plan view on the line 3—3 of FIG. 2;

FIG. 4 is an end elevational view on the line 4—4 of FIG. 2;

FIG. 5 is a bottom plan view on the line 5—5 of FIG. 2; and

FIG. 6 is an end elevational view on the line 6—6 of FIG. 2.

I claim:

The ornamental design for a roll holder for dispensing sandpaper, as shown and described.
